UNITED STATES PATENT OFFICE.

WILLIAM J. GOLIGHTLY, OF KOKOMO, INDIANA, ASSIGNOR TO PITTSBURGH PLATE GLASS COMPANY, OF PITTSBURGH, PENNSYLVANIA, A CORPORATION OF PENNSYLVANIA.

PROCESS OF SUPPLYING ABRASIVE TO GLASS-GRINDING APPARATUS.

1,136,328.

Specification of Letters Patent.

Patented Apr. 20, 1915.

Application filed June 13, 1911. Serial No. 632,979.

To all whom it may concern:

Be it known that I, WILLIAM J. GOLIGHTLY, a citizen of the United States, residing at Kokomo, in the county of Howard 5 and State of Indiana, have invented certain new and useful Improvements in Processes of Supplying Abrasive to Glass-Grinding Apparatus, of which the following is a specification.

10 The invention relates to a process for supplying sand to glass grinding apparatus. It has for its principal objects; the provision of a process in which the sand may be supplied economically and conveniently and 15 with the proper proportion of water; and the provision of a process in which the abrasive may be re-used and in which the labor of manually handling the sand is substantially eliminated. The apparatus preferably employed 20 in carrying out the process is the same as that shown in my pending application, Serial Number 626,803, filed May 12, 1911, such apparatus being illustrated in the accompanying drawings, wherein:—

25 Figure 1 is a diagrammatic plan view of the apparatus, Fig. 2 is a side elevation of the apparatus of Fig. 1, and Fig. 3 is a section on the line III—III of Fig. 1.

As shown in Figs. 1, 2 and 3, 1 is the 30 grinding table which may be of any approved form; 2 and 3 are the runners; 4 is a ditch into which the abrasive and water from the grinding table 1 is discharged; 5 is a pit to which the ditch 4 discharges 35 through the passage 6 (Figs. 1 and 3); 7 is an over-flow passage leading from the pit 5; 8 is a centrifugal pump for elevating the mixture of sand and water discharged to the pit 5; 9 is a delivery tank located above 40 the grinding table 1, and having an inclined delivery pipe 10, leading to the table; 11 is the pipe leading from the pump 8 and discharging into the upper end of the tank 9; 12 is an over-flow pipe leading from the 45 tank 9; and 13 is a water supply pipe leading into the upper end of the pipe 10.

In operation the mixture of sand and water from the ditch 4 flows into the pit 5 and is pumped up to the tank 9 through the 50 pipe 11. The finer particles of sand are carried out of the tank 9 with the over-flow water which passes through the pipe 12, while the heavier, and larger particles of sand settle in the tank 9 forming a relatively 55 thick mixture. The sand which thus set-

60 tles in the tank 9 is washed to the table 1 by means of the inflow of water through the pipe 13, the flow through such pipe being regulated by means of the valve 14, so as to provide the necessary quantity of sand 65 and the proper proportion of sand and water. The flow of water from the pipe 13 acting upon the sand in the lower portion of the tank washes away the extreme lower portions of such sand and undermines the 70 portions thereabove, so that packing and clogging of the sand is avoided, and a free and uninterrupted flow of the mixture is secured as long as the valve 14 is open. There is thus no difficulty in getting the 75 sand into suspension after it has once settled in the tank 9, and the abrasive may be repeatedly re-used, the over-flow 12 taking care of the finer particles which are too small for effective use in the grinding operation. The provision of the flow of water through the lower portion of the abrasive from the pipe 13 avoids the necessity, which would otherwise be present in apparatus of 80 this character, of the provision of means for maintaining the sand in the tank in suspension in order to permit settling and to secure a proper discharge through the outlet pipe 10. In case the use of the apparatus is discontinued and all the sand which has 85 been in suspension settles in the tank, the practice of the method as above described permits of the bringing of the sand into suspension for use without difficulty.

Having thus described my invention and 90 illustrated its use, what I claim as new, and desire to secure by Letters Patent is the following:—

1. The process of supplying abrasive to 95 glass grinding apparatus which consists in conducting the drainage from the grinding apparatus and including a mixture of water with all the utilizable grades of abrasive directly to the upper portion of a settling receptacle, eliminating the surplus water 100 and finer abrasive from the upper portion of the receptacle permitting the coarser abrasive to settle into the lower portion of the receptacle, and forcing out such coarser abrasive to the grinding apparatus by the application of fluid under pressure to the lower portion of the receptacle.

2. The method of supplying abrasive to 105 grinding mechanism, which consists in conducting the drainage containing the coarsest 110

grades of abrasive directly from the grinding mechanism to a single settling receptacle, settling the mixture of water and abrasive in the receptacle to a consistency thicker than that which is required in the grinding operation, supplying the mixture from the lower portion of the receptacle to the grinding mechanism, and adding more water to the mixture as it leaves the receptacle to dilute it to proper consistency during the step

of supplying the mixture to the grinding mechanism.

In testimony whereof I have hereunto signed my name in the presence of the two subscribed witnesses.

WILLIAM J. GOLIGHTLY.
